UNITED STATES PATENT OFFICE.

AMOS B. KREBS, OF BOLIVAR, PENNSYLVANIA.

CLOTHES-PROTECTOR.

1,136,346.

Specification of Letters Patent.

Patented Apr. 20, 1915.

Application filed February 3, 1912. Serial No. 675,240.

To all whom it may concern:

Be it known that I, AMOS B. KREBS, a citizen of the United States, residing at Bolivar, in the county of Westmoreland and State of Pennsylvania, have invented new and useful Improvements in Clothes-Protectors, of which the following is a specification.

My invention relates to the class of clothes protectors and aims to provide a protector in the form of a receptacle which may be easily manufactured and placed upon the market at a very small cost.

With the above and other objects in view my invention relates to such details of construction and in the arrangement and combination of parts as will be hereinafter fully described and specifically pointed out in the appending claims.

In describing my invention in detail reference will be had to the accompanying drawings wherein like characters denote like or corresponding parts through the several views and in which:—

Figure 1 is a front view of one form of my invention. Fig. 2 is a detail sectional view illustrating the fold at the side edges thereof. Fig. 3 is a vertical sectional view illustrating the hanger within the device. Fig. 4 is an enlarged detail view illustrating 25 clasp employed in the various forms. Fig. 5 is a front view illustrating the upper portion of a modified form of device. Fig. 6 is a front view illustrating still another modified form of device, partly broken away. Fig. 7 is a detail sectional view illustrating 30 the fold at the open edges of the device of Fig. 6.

In the accompanying drawings which 40 fully illustrate the preferred form of my invention, together with different modified forms of the same, the body portion comprises the sections 1 and 2, the said sections being pasted together at their upper and lower ends as shown at 3. The sides of the sections 1 and 2 are folded as shown at 4 and again folded as at 5, whereby a perfect air tight joint is had. For the purpose of holding the ends in place as shown I provide the clips 6 the construction of which is well known. The clips 6 are connected together

by the ribbon 8 for obvious purposes, however, I do not limit myself to this specific construction.

For the purpose of supporting the clothes between the sections 1 and 2 I provide a 55 strip which strip is held in place by means of the tops of the sections, they being securely pasted together. Connected to the lower end of the strip 9 is a cross arm 10 in the form of a coat hanger, however, I do 60 not limit myself to this. It will now be readily seen that the clips 6 may be removed from the sides of my invention and different pieces of clothing, such as furs and the like inserted between the sections. After 65 the clips have been again secured in place as shown dust and germs of all kinds cannot enter between the sections thereby preserving the clothing.

In Fig. 5 I have illustrated a modified 70 form of my invention. In this form I only provide the clips 6 in one side of the sections 1 and 2, the other sides being pasted together and folded as shown at 11.

In Fig. 6 I have again illustrated a modified form of my invention. In this figure I provide only one section of material which section is bent intermediate its ends as shown at 12, the ends meeting in the rear and being folded as shown at 13. The bottom of the 80 section is folded as shown at 14, whereby, like the forms above, germs of all kinds are prevented from entering between the sections.

I desire it to be understood that I may 85 make slight changes in the construction of the preferred and modified forms of my invention without departing from the spirit thereof, provided, however, such changes fall within scope of the subjoined claims. 90

Having thus fully described my invention what I claim as new and desire to secure by Letters Patent is:—

1. In a device of the character described, sections of material having their upper and lower ends secured together, the sides of said sections being folded to close the device, clasps engaging said folded portions, means connecting said clasps together, means connected to said last named means adapted to 100

2
extend between said sections, and a coat hanger supported by said last named means for the purpose described.

2. In a device of the character described, 5 sections of material having their upper and lower ends secured together the sides of said sections being folded to close the device, clasps engaging said folded portions, a ribbon connecting said clasps together, a strip

connected to said ribbon and extending between said sections, and a coat hanger supported by said strip for the purpose set forth. 10

AMOS B. KREBS.
